Primary Examiner — Leanne Was-Englehart*(74) Attorney, Agent, or Firm* — Schwabe Williamson & Wyatt, P.C.(57) **CLAIM**

We claim the ornamental design for a lantern, as shown and described.

DESCRIPTION

FIG. 1 is a perspective view of the lantern;
FIG. 2 is a front elevation view of the lantern of FIG. 1;
FIG. 3 is a rear elevation view of the lantern of FIG. 1;
FIG. 4 is a side elevation view of the lantern of FIG. 1;
FIG. 5 is a side elevation view of the lantern of FIG. 1, with the lantern turned 180 degrees from FIG. 4;
FIG. 6 is a top plan view of the lantern of FIG. 1;
FIG. 7 is a bottom view of the lantern of FIG. 1; and,
FIG. 8 is a perspective view of the lantern of FIG. 1 except that the lantern handle is in a raised position.
The broken lines depict portions of the lantern that form no part of the claimed design.

1 Claim, 5 Drawing Sheets(56)
